CHAIR SEAT

Theodore Kordel Linder, Memphis, Tenn.

Application May 21, 1940, Serial No. 336,478

2 Claims. (Cl. 155—187)

This invention relates generally to the class of chairs and seats and pertains particularly to improvements in chair seats and means for securing the same in position.

The primary object of the present invention is to provide a new and novel means of securing to a chair frame a seat unit, particularly a seat unit formed of woven material, whereby such seat unit may be drawn firmly into position; the material will be drawn around and cover the seat frame forming bars of the chair and the means by which the seat is secured will be effectively hidden from view.

Another object of the invention is to provide an improved chair seat construction which may be made up as a unit and which is designed to be readily attached to a chair seat frame as a replacement seat, the improved seat unit being of such character that no particular knowledge or skill is required in applying it to a chair frame and at the same time the method of securing it in position is such that it will present the appearance of having been professionally done.

The invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed in the appended claims.

In the drawing:

Fig. 1 illustrates a view in bottom plan of a chair seat constructed in accordance with the present invention, showing the same applied to a chair seat frame, the chair legs being in transverse section.

Fig. 2 is a sectional view on the line 2—2 of Fig. 1.

Fig. 3 is a transverse sectional view through a modified construction illustrating another means of clamping the ends of the strips of seat material.

Fig. 4 is a transverse sectional view similar to Fig. 3, showing still another modification of the material clamping means.

Fig. 5 is a view in perspective of an end portion of one clamping bar by which the ends of the seat material at one side of the chair are secured.

Referring now more particularly to the drawing, the numeral 1 designates the four legs or posts of a chair between which extend the side rails 2 and front and back rails 3 and 4, re-

spectively, which make up the chair seat frame to which the seat is secured.

The seat unit embodying the present invention is indicated generally by the numeral 5 and is here shown as being made up of strips 6 of interwoven material such as fabric, caning or other material which is used in the manufacture of chair seats.

Each of the four sides of the seat unit has extending therewith a clamping bar, which is indicated generally by the numeral 7. Each of these clamping bars, as shown in Figs. 1, 2 and 5 has spaced jaw portions 8 and 9, which are integrally joined together by the cylindrical connecting portion 10. It will be readily seen upon reference to Fig. 5 that the jaw bar may be shaped from a single strip of metal bent along its longitudinal center so as to produce the connecting portion 10 and the opposing jaws 8 and 9. Since the metal is preferably steel, it will have some resiliency and an inherent tendency to separate the jaw portions 8 and 9 when such portions are unconnected, therefore, the part 10 substantially functions as a spring hinge between the jaws.

Each of the clamping jaws is provided with a substantially centrally located longitudinally extending pressed out portion, thus providing one jaw, such as the jaw 8 of Fig. 5, with a rib 11 upon its inner side and the other jaw with a channel 12 upon its inner side into which the rib 11 may enter when the jaws are pressed together. The channel 12 is of materially greater width than the rib 11 so as to allow for the depression into the channel by the rib 11 of the ends of a group of the strips 6, in the manner clearly shown in Fig. 2.

Each of the bars 7 is provided at each end with a longitudinally aligned series of apertures 13 and with a single aperture 14. These apertures are, of course, extended through both jaws of the bar so that suitable securing bolts or rivets may be passed therethrough. In the construction or assembly of the seat unit, there is first arranged a group of the strips 6 all extending in parallel relation and the ends of the strips are inserted between the jaws of a gripping bar and the jaws are then drawn together so as to secure the strips therebetween in the manner shown in Fig. 2, and are secured by means of a rivet or bolt 15 which is passed through the apertures 14. The strips for the oppositely extending group are then woven through the strips of the first group and they have their ends secured to gripping bars in the

same manner so that the pair of bars connected with one group of strips extends at right angles to the bars connected with the other group of strips and the ends of the groups of strips are then disposed across the chair seat frame bars so that the gripping bars may be swung under the seat and brought into the relation in which they are shown in Fig. 1. It will thus be seen that when the gripping bars for the four sides of the seat unit are brought into operative position, each gripping bar will have each of its ends in crossed relation with an end of an adjacent bar. By this means the apertures 13 in the overlapping or crossed ends of the bars may be brought into alignment to receive coupling bolts 16, by which the gripping bars are held rigidly together in the form of a rectangular frame located at the under side of the seat. Obviously, since several apertures 13 are provided at the ends of the gripping bars, the extent of overlap of these bar ends may be regulated so as to draw the seat strips tightly or permit them to sag or remain slightly loose as may be desired.

In Fig. 3, a slight modification of the manner of securing the ends of a group of strips to a gripping bar is illustrated. In this figure, the gripping bar is indicated generally by the numeral 17, and like the bar 1 may be formed of a single strip of material and shaped to provide opposing jaw portions 18 and 19 connected by an integral resilient hinge portion 20. The jaws 18 and 19 are provided with a rib and a channel indicated at 21 and 22, respectively. The seat bottom material has an edge secured between the jaws in the manner shown, but the material is illustrated as having a portion of the edge folded over to form a longitudinally extending edge loop 23 and in this loop a rod 24 is disposed which is located within the tubular hinge portion 20. This construction is particularly well suited for securing light weight or relatively thin seat material and by folding a portion of the edge of the material over the rod 24, it will be readily seen that the edge of the material will be effectively prevented from slipping out from between the jaws of the clamping bar.

Fig. 4 illustrates a further modification of the means of securing an edge of the seat material. In this method of securing the material, the use of a rod, as in Fig. 3, is also made, the rod here being designated 25. The clamping bar is indicated as a whole by the numeral 26 and like the bars 1 and 17, may be formed of a single strip of material folded longitudinally to form the upper and lower jaws 28 and 29 connected by the resilient hinge portion 30 which is substantially tubular in cross-section. However, the jaws 28 and 29 are not provided with the interlocking rib and channel as in the structures shown in Figs. 3 and 5, but are left flat. By folding the rod 25 into a hem or overturned edge

of the seat body and locating this rod in the hinge portion 30 in the manner illustrated, it will be readily apparent that when the jaws 28 and 29 are coupled together, the material will be securely held against slipping from between them.

From the foregoing, it will be readily seen that there has here been disclosed a novel means of securing a chair seat body to a chair seat frame which makes it possible for anyone to apply the seat or replace an old seat, and which also makes it possible to secure the seat tightly in position and to effectively cover or hide the securing means from view.

While the seat illustrated and described is made up of interwoven strips of seat material, it will be readily apparent that the securing means disclosed may be effectively employed for holding in position upon the chair seat frame a single or one-piece body of material, if desired. In this case, it will be obvious that the clamping bars will receive the unbroken edges of the sheet of material in place of the ends of the adjacent strips 6 and that such bars after having jaws clamped together, will be coupled one with the other where the ends overlap, in the same manner as shown in Fig. 1.

What is claimed is:

1. In a seat construction for a chair having a seat frame, a seat body having bordering edge portions adapted to be drawn around the sides of the frame, an elongated rigid member secured along each of the edges of the seat body and disposed at the under side of the frame, the members being arranged so that each will have an end adjacent an end of another member, and separable means for adjustably coupling each end of each of the said members to the adjacent end of one of the other members at selectable predetermined locations thereon to facilitate drawing the seat body to varying degrees of tightness on and over the top of the frame.

2. A seat construction, comprising a frame, a seat body adapted to overlie the frame and having bordering edge portions extending around the sides of the frame to the under side thereof, an elongated clamping bar extending along each of said edge portions and comprising a pair of jaw members integrally connected together for relative movement, each of said jaw members having part of the adjacent seat portion disposed therebetween, means securing the jaws in clamping relation with the interposed part of the seat, each of said bars at each end having a longitudinally extending series of apertures therethrough, each bar having its apertured end in overlapping relation with the apertured end of the adjacent bar, and connecting members extending through apertures in the overlapping ends of the bars to couple said bars together.

THEODORE K. LINDER.
